United States Patent Office

Des. 218,419

Patented Aug. 18, 1970

218,419

SECRETARY CHAIR

Bernard David Nightingale, 36 Prince Arthur Ave.,
Toronto, Ontario, Canada

Filed Feb. 1, 1968, Ser. No. 10,392

Term of patent 14 years

Int. Cl. D6—01

U.S. Cl. D15—1

FIG. 2

FIG. 3

FIG. 1 is an upper front perspective illustration of a secretary chair embodying the said design;

FIG. 2 is a top plan view of the secretary chair shown in FIG. 1; and,

FIG. 3 is a rear elevational view of the secretary chair shown in FIG. 1.

I claim:

The ornamental design for a secretary chair, as shown.
